ATTORNEY

UNITED STATES PATENT OFFICE

LOUIS ROESSLER, OF ROCHESTER, MINNESOTA

WEIGHT-SUPPORTING MEANS FOR HOSPITAL BEDS

Application filed July 22, 1929. Serial No. 380,099.

This invention relates to weight supporting means for hospital and other beds, where it is required to attach weights to the limbs of patients, the general object of the invention being to provide a bracket which can be easily and quickly attached to a bed, with a pulley attached to a depending part of the bracket whereby the cable which connects the weights with the limb of the patient can 10 be passed through the pulley.

This invention also consists in certain other features of construction and in the combination and arrangement of the several parts, to be hereinafter fully described, illustrated in the accompanying drawing and 15 specifically pointed out in the appended claims.

In describing the invention in detail, reference will be had to the accompanying 20 drawings wherein like characters denote like or corresponding parts throughout the several views, and in which:—

Figure 1 shows two of the devices in use.

Figure 2 is a vertical sectional view 25 through a part of the device and through a part of the bed.

Figure 3 is a horizontal sectional view.

In these views, A indicates a bracket which is composed of the three arms 1, 2 and 30 3, the device being of substantially T shape, with the arms 1 and 2 having their end portions of curved construction and the arm 3 has its inner portion looped, with one arm 35 of the loop extended and formed with an eye 4 which receives the hook or eye of the pulley 5. The loop portion of the arm 3 and the arms 1 and 2 are covered with rubber or other suitable material, as shown at 6. The loop part of the arm 3 is placed over the 40 top of the rear end of the bed, as shown in Figure 1, with the arms 1 and 2 engaging the upright rods of the end of the bed so that the extended part of the arm 3 projects downwardly and rearwardly from the rear 45 end of the bed so that the cable 7, which connects the weights 8 with the limb of the patient occupying the bed can pass through the space between two of the upright bars of the rear end of the bed, whereby a direct 50 pull is exerted on the limb by the weights.

As will be seen, the device can be easily and quickly attached to a bed or removed therefrom and the covering 6 prevents the device from marring the bed.

It is thought from the foregoing description that the advantages and novel features of the invention will be readily apparent. 55

It is to be understood that changes may be made in the construction and in the combination and arrangement of the several 60 parts, provided that such changes fall within the scope of the appended claims.

What I claim is:—

1. A bracket for supporting a weight attached to the limb of an occupant of a bed, 65 comprising a horizontal member adapted to bear against a pair of upright bars at the end of a bed at one side thereof, a vertical member having one end attached to the center of the horizontal member, said vertical member passing through the uprights to the other side of the end of the bed and being looped to fit over the top rail and then passing to the first named side to bring the other end of said vertical member to the same side 70 as the horizontal member and weight supporting means on said other end of the vertical member.

2. A bracket for supporting a weight attached to the limb of an occupant of a bed, 75 comprising a horizontal member adapted to bear against a pair of upright bars at the end of a bed at one side thereof, the ends of the horizontal member curving forwardly, a vertical member having one end attached 85 to the center of the horizontal member, said vertical member passing through the uprights to the other side of the end of the bed and being looped to fit over the top rail and then passing to the first named side to bring the other end of said vertical member to the same side as the horizontal member and weight supporting means on said other end of the vertical member. 90

3. A bracket for supporting a weight attached to the limb of an occupant of a bed, comprising a horizontal member adapted to bear against a pair of upright bars at the end of a bed at one side thereof, a vertical member having one end attached to the cen- 95

ter of the horizontal member, said vertical member passing through the uprights to the other side of the end of the bed and being looped to fit over the top rail and then passing to the first named side to bring the other end of said vertical member to the same side as the horizontal member, weight supporting means on said other end of the vertical member and a covering of resilient material for those portions of the horizontal member and the vertical member which contact the bed.

In testimony whereof I affix my signature.
LOUIS ROESSLER.
